(57) **CLAIM**

The ornamental design for a practice ball cart, as shown and described.

DESCRIPTION

FIG. 1 is a front perspective view of a practice ball cart according to a first embodiment;

FIG. 2 is a front view thereof;

FIG. 3 is a rear view thereof;

FIG. 4 is a right side view thereof, the left side view being a mirror image;

FIG. 5 is a top view thereof;

FIG. 6 is a front perspective view of a practice ball cart according to a second embodiment;

FIG. 7 is a front view thereof;

FIG. 8 is a rear view thereof;

FIG. 9 is a right side view thereof, the left side view being a mirror image;

FIG. 10 is a top view thereof;

FIG. 11 is a front perspective view of a practice ball cart according to a third embodiment;

FIG. 12 is a front view thereof;

FIG. 13 is a rear view thereof;

FIG. 14 is a right side view thereof, the left side view being a mirror image; and,

FIG. 15 is a top view thereof.

The broken lines shown in the drawings illustrate portions of the article that form no part of the claimed design. The second and third embodiments are shown with symbolic breaks, and those portions of the article between the break lines form no part of the claimed design.

1 Claim, 15 Drawing Sheets
